UNITED STATES PATENT OFFICE

WILLIAM R. HOWELL, OF PHILADELPHIA, PENNSYLVANIA

DESIGN FOR A TOY ANIMAL

Application filed March 10, 1930. Serial No. 34,803. Term of patent 7 years.

To all whom it may concern:

Be it known that I, WILLIAM R. HOWELL, a citizen of the United States, residing in Philadelphia, county of Philadelphia, and State of Pennsylvania, have invented a new, original, and ornamental Design for Toy Animal, of which the following is a specification, reference being had to the accompanying drawing, forming a part thereof.

In the drawing, Figure 1 is a top plan view; Fig. 2 is a side elevation and Fig. 3 is a front elevation of a toy animal showing my new design.

I claim:

The ornamental design for a toy animal, as shown.

WILLIAM R. HOWELL.
